AIR-HEATER.

1,227,324.

Specification of Letters Patent.

Patented May 22, 1917.

Application filed January 30, 1914, Serial No. 815,507. Renewed November 17, 1915. Serial No. 62,075.

To all whom it may concern:

Be it known that we, PERCY RUSSELL, FRANK J. SEPAS, and EDWARD B. WILFORD, citizens of the United States, residing in 5 the city of Brooklyn, county of Kings, State of New York; city of Philadelphia, county of Philadelphia, State of Pennsylvania, and Merion borough, county of Montgomery, State of Pennsylvania, respectively, have 10 invented certain Improvements in Air-Heaters, of which the following is a specification.

One object of our invention is to provide a relatively efficient device particularly designed to heat a flowing body of air as required in dental syringes and like instruments; it being especially desired that the construction shall be such as to prevent objectionable heating of the exterior portions 20 of the device and consequent lowering of the efficiency of the apparatus.

We also desire to provide a device for electrically heating air, which in addition to being substantial and relatively inexpensive to construct, shall be convenient to use and safe to operate.

Another object of the invention is to provide a novel form of air heating device in which the heat generating element may be 30 conveniently removed or replaced for the purpose of inspection, repair, etc., and in which the air is caused to take a tortuous course with a view to preventing the external portions of the apparatus from becoming highly heated.

These objects and other advantageous ends we secure as hereinafter set forth, reference being had to the accompanying drawings, in which:—

40 Figure 1 is a longitudinal vertical section of a part of a hot air syringe constructed according to our invention;

Figs. 2, 3 and 4 are respectively transverse vertical sections on the lines *a—a*, *b—b* 45 and *c—c*, of Fig. 1;

Fig. 5 is a vertical section of a detail of the invention, and

Fig. 6 is a perspective view of one end of the heating unit.

50 In the above drawings, 1 represents a metallic tube internally threaded at one end and externally threaded at the opposite end. On this latter end is threaded an inwardly

flanged sleeve 2, while the other end has threaded into it a sheath 3 of some material 55 which is a non-conductor of heat and electricity.

A metallic member 4, constituting a connector, extends into the flanged end of the sleeve 2, to which it is rigidly connected by 60 a second sleeve 5 having at one end an inwardly extending flange 6 and co-operating with an annular shoulder 7 on the connector 4, from which, however, it is electrically insulated by a ring 8, of fiber, mica, 65 or the like. This second sleeve 5 likewise has an annular shoulder 9, between which and the flange of the sleeve 2 is confined a second insulating ring 10.

With the above described construction, 70 the second sleeve 5 is spaced away from the connector 4 and has a series of holes 12, whereby air may pass from the annular space around the connector to the annular space between the sleeves 5 and 2;—such 75 air being free to pass from this latter space between the second sleeve and the tube 1 to the interior of the main portion of the latter. The connector 4 at one end is internally threaded for the reception of the air 80 supply pipe 13, and it also has a series of radially extending holes 4^a, through which air is free to pass from this supply pipe to the annular space within the second sleeve 5. The part of the air supply pipe 13 immediately adjacent its threaded end above referred to is tapered and has rotatably mounted on it a valve 14 in the form of a sleeve internally bored to fit said tapered portion and in addition having an elongated 90 internal slot or recess 15 extending parallel with its axial line in position for connecting two radially extending passages 16 and 17 leading respectively to the interior of the connector 4 and to the source of air. By 95 rotating the valve 14 it is thus possible to cut off or establish communication at will between these passages 16 and 17, and we preferably provide a spring washer 18 between the valve and the adjacent end of the connector 4, whereby said valve is at all times kept in air-tight contact with the tapered end of the supply pipe 13.

Mounted on and fixed to the valve 14 is a suitable handle 19 of some insulating material, such as hard rubber or the like, pref-

erably having a corrugated or ribbed external surface and recessed at one end to receive the projecting ends of the connector 4 and of the sleeve 5. In order to limit the 5 possible angle through which the handle 19 with the valve 14 may be turned relatively to the supply pipe 13, we provide a key 20 driven into or otherwise attached to said handle and projecting into a recess 21 10 formed in a flange 22 of the pipe.

Extending longitudinally through the handle 19 is an electric conductor 23, to which is electrically connected a spring contact member 24 yieldingly engaging the 15 outer cylindrical surface of the sleeve 5, and one terminal of an electric circuit may be connected to this member 23, while the other terminal of such circuit is connected to the supply pipe 13.

20 The outer casing 1 just inside its internal threads has an inwardly projecting shoulder 26 against which a ring 27 of suitable 25 insulating material is held by means of a notched ring 28 Fig. 5 abutting against the adjacent end of a tube forming an inner casing 29, whose opposite end is electrically insulated by a non-conducting ring 31 from a shoulder 30 at the inner end of the connector 4. This casing 29 is substantially 30 concentric with the outer casing 1 from whose inner surface it is spaced away, and the notches of the ring 28 form passages 37 between said ring and the adjacent end of said casing 29, through which air is free 35 to pass into the space between the inner casing surface and a metallic tube 32. This latter extends concentrically within the inner casing 29, being inwardly flanged at one end and provided with an insulating 40 lining 33.

Mounted within said tube and forming with it a removable heating unit is an elongated coil or other body of wire or current conductor, preferably having a high 45 specific resistance as well as a high melting point, and while one end of this coil is sweated into or otherwise electrically connected to a screw 34, its other end is engaged and supported by a suitably formed 50 bar 35 extending across the opposite end of the tube 32 as shown in Fig. 6. Said bar is preferably cross shaped with two of its extremities removably held in an annular recess in the end of the tube 32 which at 55 two opposite points 50 is notched so as to hold the two other ends of said bar for the purpose of preventing its rotation. The coil 43 is maintained in a state of tension and is preferably formed on a mandrel of 60 other than circular section, after which each of its convolutions is rotated through a small angle relatively to those on either side of it, as shown in Fig. 2, in order that so far as possible they may not lie in line with 65 or cover each other. This heating unit is

rigidly held to the connector 4 by the screw 34 threaded centrally into the same and rigidly connected to the inwardly flanged end of the tube 32 by a pair of nuts, which, however, are electrically insulated from it. 70

Air passages 36 are provided through the side walls of the tube 32 and its lining, immediately adjacent the screw 34 and there is an annular space between it and the inner surface of the casing 29, which is connected by openings 37 with the space between said inner casing and the outer casing 1. 75

The nozzle 38 of the syringe has sweated or otherwise fixed to its base a ball 39 which is rotatable within a socket 40 formed by a sleeve threaded into the sheath 3. The outer edge of this socket sleeve is bent inwardly as shown, in order to retain the ball in place and there is a spring 41 confined between a retaining flange 42 of said socket 85 and the ball, so that the latter is at all times kept in air-tight engagement with the inwardly curved portion of said socket 40.

Under conditions of use the electric current flows from a suitable supply conductor 90 to the member 23, thence through the spring 24 to the ring 5, through the inner casing 29, notched piece 28, end of tube 32, and cross-bar 35 to one end of the heating coil 43. From the other end of this latter the 95 current flows to the screw 34, thence to the connector 4 and to the supply pipe 13. If now air be delivered to the supply pipe 13 and the handle 19 be rotated so that the recess 15 of the valve is in the position 100 shown in Fig. 1, connecting the parts 16 and 17 of the passage in said conduit, such air will flow into the connector 4, out through the openings 4^a thereof, thence through the openings 12 of the sleeve 5, into 105 the space between the inner casing 29 and the outer casing 1 and so to the forward end of the device adjacent the nozzle. From here it passes into the space between the inner casing 29 and the tube 32, thence to the 110 rear or inner end of said tube and through the openings 36 into the interior thereof. The air thus admitted passes forward through the heating unit and is effectively heated by its intimate contact with the 115 heated convolutions of the wire 43, being finally allowed to pass in a heated condition into the nozzle 38, from the end of which it escapes. As will be understood by those skilled in the art, the flow of the cool 120 air over the inner surface of the outer casing 1 keeps this at a low temperature regardless of the fact that the air within the tube 32 is at a high temperature, and any heat radiated from said tube is carried by the air back into the heating chamber and finally out through the nozzle. 125

By the use of the heat insulating sheath 3, any material conduction of heat from the nozzle to the outer casing is effectually pre- 130

vented, and the likelihood of any discomfort to a patient from contact with said sheath 3 is diminished by corrugating or knurling its external surface.

- 5 If for any reason it should be desirable to remove the heating unit formed by the cartridge tube and its heating coil, it is only necessary to unscrew the insulating sheath 3 from the outer casing 1, thus removing the 70
 10 nozzle 38 and exposing the outer end of said tube. This is provided with oppositely disposed recesses 50, which, in addition to holding the ends of the bar 35, are designed for the reception of a screw-driver and by this 75
 15 means it is possible to rotate said tube so as to withdraw the screw 34 from the connector 4, whereupon said tube may be removed from the remainder of the device.

By the mounting and construction of the 20 nozzle and its associated parts, it is possible to move it into any of a number of positions at different angles to the general line of the casing 1.

We claim:—

- 25 1. The combination in an air heater of a casing having an inlet; an outlet conduit; a heating unit in the casing connected to receive air from the inlet and deliver it to the outlet conduit; with a non-conducting 90
 30 sheath removably connecting the casing and the outlet conduit, and extending over that part of said conduit adjacent the casing.

2. The combination in an air heater of a 35 casing having an inlet; an outlet conduit; a heating unit in the casing connected to receive air from the inlet and deliver it to the outlet conduit; a socket carried by the casing; a ball member attached to the outlet 100
 40 conduit and operative in the socket; and a spring in said socket operative upon the ball structure to cause the latter to make a tight joint with said socket.

3. The combination in an air heater of a 45 casing having an inlet; an outlet conduit; a heating unit in the casing connected to receive air from the inlet and deliver it to the outlet conduit; with a ball and socket joint connecting the casing and the outlet 110
 50 conduit and including a heat insulating sheath.

4. The combination in an air heater of a 55 casing having an inlet and an outlet; a heating unit consisting of a tube detachably screwed into said casing and communicating with said inlet and outlet; and a heating coil suspended in said tube.

5. The combination in an air heater of a 60 casing; a handle having two electric conductors, of which one is an air conduit; a tube in the casing; an electric conductor in the tube having one end electrically connected thereto and its other end electrically connected to said air conduit; and an inner casing 125
 65 electrically connected to said tube and to the second electric conductor.

6. The combination in an air heater of a casing; a handle having two electric conductors, of which one is an air conduit; a tube in the casing; an electric conductor in the tube having one end electrically connected thereto and its other end electrically connected to said air conduit; an inner casing 130
 70 electrically connected to said tube and to the second electric conductor, there being 75
 75 passages for conducting air from the conduit in the handle to the tube; with an outlet conduit connected to receive the air from said tube.

7. The combination in an air heater, of a casing having an inlet; an outlet nozzle for 80
 85 said casing; a connector in the casing; two tubes, of which one abuts on but is insulated from the connector, and the other is threaded to said connector; with a heating coil in the second tube and removable therefrom with from the casing.

8. The combination in an air heater, of a conduit; a connector mounted thereon and having air passages; a casing mounted to receive air from said passages; a sleeve in 90
 95 said casing receiving air therefrom; an outlet nozzle; and a tubular heating unit removably mounted in the sleeve in position to heat air therefrom and deliver it to the nozzle.

9. The combination in an air heater of at 100
 least three nested substantially concentric tubes of progressively increasing diameters; means for maintaining the intermediate one of said tubes in a state of compression and 105
 the inner and outer tubes in a state of tension; with a heating coil in the innermost tube.

10. The combination in an air heater of a 110
 115 tubular casing; a heating unit therein consisting of a tube provided with a threaded end portion electrically insulated from its body and a heating coil having its ends respectively connected to said body and to said end portion; an outlet nozzle for the 120
 125 casing; a metallic connector having the end portion of the heating unit removably screwed into it; with means for conducting electric current to the body of the tube and to said metallic connector.

11. The combination in an air heater, of a tubular casing; a heating coil in said casing; an outlet nozzle at one end of the casing; a connector at the opposite end of the casing having an air inlet passage and electrically connected to one terminal of the heating coil; with a tubular structure surrounding said coil within the casing and connected to the other terminal of the coil.

12. The combination in an air heater, of a tubular casing; a heating coil in said casing; an outlet nozzle at one end of the casing; a connector at the opposite end of the casing having an air inlet passage and electrically connected to one terminal of the 130

heating coil; with a tubular structure surrounding said coil within the casing in position to serve as a baffle for the air flowing from the passage of the connector 5 through the casing to the nozzle.

13. The combination in an air heater of a tubular casing; two sleeves mounted concentrically within the same and including means coacting therewith to form a tortuous 10 air passage; a heating coil carried by and freely suspended within the inner sleeve and removable therewith as a unit from the other sleeve and from the casing; a source of current connected to one of the sleeves and to 15 one end of said coil; and means for electrically connecting said sleeve to the second end of the coil.

14. The combination in an air heater, of a tubular casing; a heating coil in said casing; an outlet nozzle at one end of the casing; a connector at the opposite end of the casing having an air inlet passage and electrically connected to one terminal of the heating coil; with a plurality of tubular 20 structures surrounding said coil within the casing in position to serve as baffles for the air flowing from the passage of the connector through the casing to the nozzle.

15. The combination in a fluid heater of 25 a plurality of sleeves fitting one inside the other to form a tortuous passage; an inlet conduit connected to deliver air to the outer portions of said passage; a heating member freely suspended within the cylindrical hole 30 low of the innermost sleeve and arranged to receive and heat air after it has flowed through said passage, one of the sleeves being connected to conduct current to one terminal of said heating member; means for 35 conducting current to said latter sleeve and the second terminal of the heating member; and an outlet conduit for the heated air.

16. The combination in an air heater of 40 a casing having an inlet and an outlet; a heating element in the casing connected to receive air from the inlet and deliver it to 45

the outlet; with means for preventing conduction of heat from the heating element to the casing, the same consisting of a member placed to direct the incoming cool air into contact with the inner surface of the casing before permitting it to pass to the heating element.

17. The combination in an air heater of 50 an outer casing having an inlet and an outlet; a heating unit in said casing connected to receive air from the inlet and deliver it to the outlet; and an inner casing mounted to conduct incoming cool air between the outer casing and the heating unit to prevent 55 heating of said outer casing.

18. The combination in an air heater of 60 an outer casing having an inlet and an outlet; a heating unit connected to receive air from the inlet and deliver it to the outlet; with an elongated inner casing interposed between the heating unit and the outer casing, provided with passages placed to first direct cool air from the inlet between the inner and outer casings and thereafter conduct such air between said inner casing and the heating unit before permitting it to pass 65 into the latter.

19. The combination in an air heater of 70 an outer casing; a tube closed at one end and mounted in said casing; a heating coil in said tube; an inner casing for conducting air to the interior of the tube adjacent the closed end thereof; and an outlet conduit connected to the casing in position to directly receive heated air discharged from the 75 tube.

In testimony whereof we have signed our names to this specification in the presence of two subscribing witnesses.
